United States Patent Office

Des. 208,164
Patented July 25, 1967

208,164

RADIO

William A. Winton, 282 Bolton St.,
Springfield, Mass. 01129

Filed Mar. 31, 1966, Ser. No. 1,710

Term of patent 3½ years

(Cl. D56—4)

FIG. 1 is a perspective view of a radio showing my new design;

FIG. 2 is a side elevational view of the radio shown in FIG. 1, the opposite side being substantially a mirror image thereof;

FIG. 3 is a front elevational view of the radio shown in FIG. 1;

FIG. 4 is a top view of the radio shown in FIG. 1; and
FIG. 5 is a rear elevational view of the radio shown in FIG. 1.

I claim:

The ornamental design for a radio, as shown and described.
